UNITED STATES PATENT OFFICE.

LOUIS C. NEFF, OF BROOKLYN, NEW YORK.

TYPE-WRITING MACHINE.

SPECIFICATION forming part of Letters Patent No. 733,258, dated July 7, 1903.

Application filed April 18, 1902. Serial No. 103,475. (No model.)

To all whom it may concern:

Be it known that I, LOUIS C. NEFF, a citizen of the United States, residing in the borough of Brooklyn, city of New York, county 5 of Kings, and State of New York, have invented certain new and useful Improvements in Type-Writing Machines, of which the following is a specification, reference being had therein to the accompanying drawings.

My invention relates to type-writing machines, especially to the escapement mechanism thereof, and more particularly to a class of escapements comprising a carriage-controlling mechanism consisting of a main- 15 spring or other means for feeding the carriage and a rack member or its equivalent and a detaining member and a spacing member adapted to successively engage said carriage-controlling mechanism to intermittently release it to effect the spacing of the carriage with each depression of a key-lever.

That the nature and objects of my invention may be more fully understood I would state that there are three general types of 25 this class of escapements, usually employing a single rack and a detaining and a spacing-dog, although the specific mechanism varies indefinitely to accommodate them to machines of different models—first, wherein the spacing is effected immediately upon the disengagement of the rear dog; second, wherein the spacing is effected immediately upon the disengagement of the forward dog, and, lastly, wherein the spacing is effected in part immediately upon disengagement of the forward 30 dog and completed immediately upon disengagement of the rear dog. There is still another class wherein the spacing is gradually effected in part during the engagement of the rear 35 dog and completed by the reengagement of the forward dog. Experience has demonstrated that the first type while satisfactory to operators of moderate speed does not meet the requirements of high-speed operators, 40 that the second type while meeting the requirements of high-speed operators as to speed of escapement requires an even regular touch to insure a proper spacing of the letters, and, furthermore, as the key-lever 45 while being depressed is suddenly relieved from the pressure exerted by the mainspring of the carriage by the disengagement of the

forward dog the touch is varying and very unsatisfactory. This type is unsuitable for other than high-speed operators having a 55 regular and uniformly even touch. The third type, possessing as it does some of the individual characteristics of the two former types, also possesses to a limited extent their individual disadvantages. The other type referred to requires very fine adjustment to insure the proper engagement of the rear dog, and also as the carrier is oscillated to a variable extent by the different key-levers the spacing is initiated at different periods of the 60 return of the type-bar. Hence the action is not uniform under all conditions, and a slow uneven touch results in a reaction on the key-lever and the finger commensurate with the weight of the carriage and the resistance 65 of the spring tension thereon.

The object of my invention, primarily, is to provide an escapement for a type-writing machine, wherein the platen-carriage will be held stationary under all conditions until the 75 type has effected its imprint and dropped free of the paper and then be instantly released to space, either wholly or in part, by the initial return of the vibratory dog-carrier, thus providing an escapement adapted to conform 80 to the requirements of all speeds of operators.

A further object is to provide an escapement wherein the initial spacing will be effected at a uniform period relative to that of the imprint, irrespective of the variance 85 in the extent of the depression of the several key-levers.

A further object is to provide an escapement which while being adapted to all speeds of operators may be adjusted to a nicety as 90 to the instant of release to meet the special demands of the individual operator as to spring tensions throughout the machine.

A further object is to provide an escapement wherein the spacing and the detaining 95 member will each be under the control of the other to insure a proper and uniform feed and the reengagement of the detaining member, and also to provide means whereby such relation may be regulated to compensate for 100 wear or to suit the requirements of the individual operator.

A further object is to provide an escapement wherein when parallel dogs are used the

dogs may be mounted in close juxtaposition prior to the interval of spacing, but will draw apart while effecting such spacing in a manner to facilitate the disengagement of the 5 rack therefrom.

A further object is to provide means for actuating the vibratory member or rocker-arm, whereby said member and the dogs carried thereby may be so adjusted as to remain 10 and to hold the carriage stationary during the initial return of the type-bar, and also means whereby the throw of said member may be regulated irrespective of the depression of the key-levers and universal bar.

15 The invention consists in providing an escapement for a type-writing machine comprising a spacing member adapted, in conjunction with a vibratory member actuated by the several key-levers, to maintain the 20 platen-carriage stationary during the direct movement of said vibratory member and to be actuated instantly with the initial return movement of said member to permit the spacing of the carriage under the tension of its 25 mainspring or other controlling mechanism, and other novel features of construction and arrangement of parts, as hereinafter set forth and described, and more particularly pointed out in the claims hereto appended.

30 Referring to the accompanying drawings, Figure 1 is a slightly-enlarged rear elevation of the vibratory mechanism and detaining and spacing members carried thereby and coöperating therewith in a state of rest, the 35 carriage and its mainspring and the means for actuating said vibratory member not being shown. Fig. 2 is a similar view showing the position assumed by the various parts in effecting the spacing of the carriage, the actuating mechanism excepting the key-lever and universal bar being shown; and Fig. 3 is a side elevation of the auxiliary vibratory member and the elements carried thereby, together with the actuating mechanism. Fig.

40 4 is a plan view of the escapement mechanism on an enlarged scale. Fig. 5 is a diagrammatic view illustrating the relation of the various elements when the escapement mechanism is at rest. Fig. 6 is a similar view 45 when the vibratory member is at the end of the direct movement. Fig. 7 is a similar view showing the relation of the various elements at the instant of the reversal of the direction of movement of the vibratory member. Fig. 50 8 is a rear elevation of a modification of my invention wherein the engaging member and its pivotal support are integral and vibratory, and Fig. 9 is a side elevation of the modification shown in Fig. 8.

55 60 Like letters refer to like parts throughout the several views.

In the accompanying drawings I have shown my invention in a form suitable for use in connection with a well-known rack and ratchet-wheel carriage-controlling mechanism, and in 65 the following description I will refer more particularly to this application of it; but the

invention is capable of adaptation to different models of machines, and the details of construction will necessarily be varied to be 70 applicable to the various models.

At A, I have shown a portion of the top plate of a type-writing machine and at B a rack, pinion, and ratchet-wheel mechanism of well-known construction, by means of which the 75 movement of the carriage under the tension of its mainspring is controlled. The construction of this carriage, being immaterial to the invention, is not shown in detail. The carriage is held stationary normally and except during the interval of spacing by means of a detaining member *a*, which engages with the ratchet-wheel of the mechanism B. The construction and arrangement of this fly-dog *a* is well-known in the art. It is journaled 80 in shoulders *a'* *a''* of the carrier-arm C and is arranged to topple, under the influence of the spring *a*², in a direction opposite to that of the course of the ratchet-wheel to insure its reengagement therewith, such reengagement 85 restoring it against the tension of said spring until it, and with it the wheel or rack and platen-carriage, is brought to a state of rest.

Hangers D D are pendent from the frame or top plate of the machine, and in these 95 hangers are mounted the auxiliary vibratory member C, which causes the detaining and the spacing members, through the carrier-arm C' thereof, to successively engage the carriage-controlling mechanism as well as the 100 main vibratory member E, which is actuated by the several key-levers and transmits motion therefrom to the auxiliary vibratory member C and thence to the carrier-arm C' by a mechanism to be more fully described hereinafter. The platen-carriage is spaced with 105 each depression of a key-lever by vibrating said carrier C', the direct throw of which disengages the detaining member *a* from the carriage-controlling mechanism and transfers 110 the pressure of the mainspring of the carriage to a spacing member. To insure a more uniform and even escapement, I provide a pivotal support *b*, adapted, by engagement directly or through an interposed engaging 115 member *d*, to sustain this pressure and to hold the carriage stationary during the entire direct throw of the said carrier member and to permit the spacing of the carriage instantly upon the initial return movement of 120 said carrier. This support is provided with an abutment or projection *b'*, adapted to contact with a stop *c* to prevent the unseating of said support upon such direct movement of 125 the carrier-arm only, said support being free to turn in the reverse direction to accomplish its unseating. In the preferred form of my invention, (shown in Figs. 1 to 7 of the accompanying drawings,) such being readily applicable to both rack and wheel machines, 130 I employ an independent engaging member *d*, interposed between said support *b* and the ratchet-wheel or rack, one face of which member engages the wheel, and a wear-face on

which, as d^2 , comes into frictional engagement with said pivotal support b to transmit there-
to the pressure of the mainspring. The ar-
rangement of the support b , the engaging
5 member d , the carriage-controlling mech-
anism B, and the stop c is such that said sup-
port under all conditions will hold the en-
gaging member stationary through frictional
10 contact of the said member during its en-
gagement with the carriage-controlling mech-
anism and the pivotal support b , and thus
sustain the pressure of the mainspring upon
the direct throw of the carrier C' and hold
the carriage stationary during this interval,
15 which includes the making of the imprint.
Immediately upon the reversal of the direc-
tion of travel of the said carrier C' this same
frictional contact serves to unseat said sup-
port, which swings upon its pivot, and through
20 the agency of the interposed engaging mem-
ber d permits the carriage to travel under
the influence of its mainspring a letter-space
or portion thereof. To restore the various
parts to their normal position, I provide a
25 spring b^2 , (torsional in the form shown,) which
merely serves to normally maintain
the projection b' and stop c in engagement
when the detaining member a reengages the
carriage-controlling mechanism. A spring d'
30 serves to restore the engaging member d to
its normal position at this time also. To per-
mit wear on the various contacting surfaces
being taken up or differences due to adjust-
ment of the various parts being compensated
35 for, I preferably mount the pivotal support
 b and its stop c upon a plate k , which is at-
tached to the machine by means of set-screws
 k' , movable in elongated slot to permit the
adjustment of said plate toward or away
40 from the carriage-controlling mechanism.

The engaging member d of the spacing
mechanism is mounted in close juxtaposition
to the detaining member a upon an inclined
fulcrum-pin carried by the carrier-arm C'.
45 As this engaging member drops forward with
the unseating of pivotal support b , the space
between the members a and d is therefore
gradually increased to facilitate the passage
therefrom of the rack or wheel. A shoulder
50 d^3 limits the return movement of the engag-
ing member d under control of its spring d^2
and insures alinement with the detaining
member a , the customary drop being pro-
vided for to insure a more perfect action of
55 these members. To prevent the escape of
the wheel from the control of the engaging
member d , to insure a uniform feed of said
member, to permit of a variation of feed of
the spacing member when desired, and to in-
60 sure a proper reengagement of the detaining
member a with the carriage-controlling mech-
anism, I place each member under the con-
trol of the other by means of an adjustable
stop e , which is carried by one of them, as d ,
65 for convenience of access thereto and pro-
vided with an engaging head or shoulder,

which is adapted to engage the other mem-
ber, as a .

The means whereby the detaining member
 a and engaging member d are caused to suc-
cessively engage the carriage-controlling
70 mechanism comprises a main vibratory mem-
ber E and an auxiliary vibratory member
C, provided, respectively, with substantially
parallel arms E' and C', having elongated
75 openings therein, respectively. These arms
are connected by a rigid link g , the upper end
of which is attached to the arm C' by means
of a set-screw h , having an offset shoulder
encompassed thereby to form a swivel con-
80 nection, which screw is seated in the opening
therein, and the lower portion of said link is
formed into an elongated loop g' , which en-
compasses a set-screw h' , seated in the open-
85 ing in the arm E', said screw being also pro-
vided with an offset shoulder to form a swivel
joint. The offset shoulder of the screw h' ,
however, is substantially elliptical or eccen-
tric and its greatest dimension is equal to
90 that of both dimensions of the loop g' . The
opposite sides of said loop g' are substan-
tially parallel, so that when the parts are in
the position shown in Fig. 3, the elliptical or
eccentric shoulder being indicated in dotted
95 lines, there will be sufficient slack in said
loop to permit a movement of the main vibra-
tory member E independently of that of the
auxiliary vibratory member C at the begin-
ning of the return throw of the former, thus
providing for a brief interval of inactivity or
100 rest of the latter upon the reversal of the
movement of the former simultaneous with
the initial return of the type-bar. This in-
dependent movement may be regulated by
turning the set-screw h' , the elliptical or ec-
105 centric shoulder thereon acting as a take-up
to vary the slack in the loop g' to a point
where such will be entirely occupied to cause
both members to move throughout in unison.
The relative throw of the vibratory members
110 may also be regulated by shifting the respec-
tive set-screws h h' in the slots in the arms
C' and E' to narrow or increase the distance
between said arms, so as to increase or di-
minish the leverage at which said arms act.
115 In the form of machine herein shown motion
is imparted to the vibratory members by
means of the cross-rod F, connecting-links G,
and universal bar H, which passes under and
is actuated by the several key-levers, one of
120 which is shown at K.

To permit the proper adjustment of the
stop c in assembling the machine or to take
up wear, I provide same with means of ad-
justment, as the set-screw c' .
125

To obtain greater speed in exceptional
cases, I provide for the partial unseating of
the support b during the direct throw of the
carrier C' by the impact of the buffer-face f' ,
carried by the buffer-spur f , with the projec-
13 tion b' . When the slack in the loop g' is en-
tirely taken up and light spring tensions are

used, there will be a tendency on the part of the carrier C' to continue the direct movement through acquired momentum subsequently to the instant of imprint. To insure 5 the unseating of the said support at the desired instant, the buffer-face f' is made adjustable in order that the instant of impact may be regulated. Under normal spring tensions the frictional contact of the carriage-controlling mechanism with the spacing member will suffice to prevent such additional movement, and this movement may also be prevented by means of the rocker-arm buffer now generally used. The adjustable buffer 10 f' is provided merely to meet the demands of special conditions when it is desired to take advantage of this additional movement through momentum, either to enable the use of lighter tensions or to increase the ease of 15 manipulation of the keys or other reasons.

The return movement of the vibratory members is accomplished by means of the spring M acting upon the main vibratory member E, said spring being adjustable.

20 In the modification shown in Figs. 8 and 9 the construction and mode of operation are substantially as in the hereinbefore-described form of the invention. To emphasize the analogy and to more clearly indicate the corresponding parts in the two forms, the same reference - letters with different exponents, however, are used to designate similar parts. The detaining member a and the plate k², carrying the pivotal support b³ and the engaging member d⁴, mounted thereon or made integral therewith, are both mounted upon and movable with the rocker-arm C'. The adjustable stop c² is also carried by and movable with said rocker-arm in order to 25 30 35 40 45 50 55 60 65 serve the proper relation thereof to the abutment or projection b⁴ on said pivotal support. The spring b⁵, acting upon said pivotal support to normally maintain the projection b⁴ in contact with the stop c², is preferably so secured to a set-screw, as b⁶, as to admit of the regulation of the tension of said spring by means of said screw. The plate k² is provided with an elongated slot or slots, as is the plate k in the preferred form, and is secured to the rocker-arm by means of the screw k³ to permit of the adjustment of the plate to take up wear. The adjustable stop f², which is mounted upon a relatively stationary part of the type-writing-machine frame in a position to have the abutment or projection b⁴ contact therewith at the end of the direct throw of the rocker-arm, corresponds in function with the vibratory buffer f in the preferred form. To limit the feed of the carriage through the engaging member d⁴ and to insure the alinement of the detaining member with the succeeding wheel or rack space in this form of the invention, I provide an offset portion on the said detaining member carrying an adjustable contact e', with which the abutment b⁴ contacts toward the end of the feed. These parts insure a mode of op-

eration analogous to that resulting from the use of the abutment e of the preferred form of invention, the adjustability of the contact e' permitting a regulation of the amount of feed of the engaging member d⁴. It is necessary that the radius of the support b³ be such as to admit of the detaining and the engaging members being placed so close together as to prevent the wheel or rack teeth passing therebetween and yet give the latter clearance of the former during the spacing interval. It is also necessary in this form that the said engaging member shall present only a single point of contact to the rack or wheel tooth to overcome any back thrust thereon when the pivotal support rotates.

The operation of the mechanism shown in Figs. 1 to 7, inclusive, is as follows: Upon the depression of a key-lever K the universal bar H is depressed thereby until the type contacts with the paper on the platen. The universal bar through the connection - wires G and cross-bar F, attached to the arm E' of the vibratory member E, actuates the said member against the tension of the spring M, a corresponding movement being transmitted through the link g, which is free to swivel at its points of attachment to admit of such movement to the auxiliary vibratory member C. To adapt the machine and escapement to operators who do not release the key promptly, slack is permitted in the loop g', thus rendering the main vibratory member E capable of slight return movement independently of and prior to transmitting such movement to the auxiliary member. This slight independent movement is sufficient to permit the type to drop free of the paper, and as the auxiliary vibratory member returns under the control of the said main vibratory member subsequently to this period the spacing is effected. If it is desired to vary the maximum throw of the auxiliary vibratory member C, the link g may be shifted by means of the set-screws h' to increase or diminish the leverage at which either of the vibratory members works relative to the other. The extent of the independent movement of the main vibratory member may also be regulated by means of the elliptical or eccentric portion of the screw h', which takes up slack in the loop g', and thus limits said movement proportionately. The carriage-controlling mechanism B, as illustrated diagrammatically in Fig. 5, is normally engaged by the detaining member a, which is mounted on the carrier C' and held stationary by the abutments a³ a³. During the engagement of the detaining member a the abutment or projection b' on the pivotal support b under the influence of the spring b² is maintained in contact with the stop c. As the detaining and engaging members are thrown on the direct movement of the vibratory members the former is disengaged from the controlling mechanism, and the pressure of the main carriage-spring is transferred to the support b by the engagement of the said

engaging member *d* with said controlling mechanism and said support, respectively. The relation of the several elements during this action is illustrated in Fig. 6. The pressure exerted on said support merely maintains the relation between the projection *b*¹ and the stop *c* during the entire direct movement of said engaging member, thus maintaining the carriage stationary. Instantly upon the initial return movement of the vibratory member *C*, however, the direction of the force of said pressure upon said support is reversed, and as it is free to rotate in the opposite direction it will be unseated, and as the parts instantly assume the position indicated in Fig. 7 the carriage will be permitted by said engaging member to feed forward. As the detaining member *a* is disengaged from the carriage-controlling mechanism *B* it topples backward under the influence of the spring *a*² preparatory to reengaging said mechanism at the next tooth in the well-known manner. As the engaging member *d* upon the initial return movement of the auxiliary vibratory member or carrier drops forward the enlarged head of the stop *e* engages said member *a*, (see Fig. 7,) causing it to move in unison with the engaging member until it engages the abutments *a*³. Owing to the adjustability of the said stop *e*, the distance traversed by said engaging member may be so regulated as to space the carriage either a full space at this period or a part space only. The engaging member *d* being mounted on an inclined fulcrum pin, as it drops forward the upper portion thereof passes gradually away from the detaining member, which admits of a construction wherein the dogs may be in close juxtaposition to facilitate the engagement of the engaging member and the carriage-controlling mechanism and wherein the said members will be spaced slightly apart at a period to facilitate the disengagement of said member and said mechanism. If the wear or the adjustment of the machine results in too great a drop from the detaining member to the spacing member, such may be compensated for by resetting the plate *k*, upon which the pivotal support is mounted.

The operation of the form shown in Figs. 8 and 9 is substantially like that of the preferred form in all essentials. As the vibratory member is actuated by the several key-levers the detaining member *a* is disengaged from the carriage-controlling mechanism, and the pressure of the mainspring thereof is transferred to the pivotal support *b*³ by the engagement of the engaging member *d*⁴ with the said carriage-controlling mechanism. The direction of pressure on said support during the direct throw of the rocker-arm is such as to hold the abutment or projection *b*⁴ in continuous engagement with the stop *c*². Upon the initial return movement thereof, however, the direction of this pressure is reversed, and the said abutment swings away from said stop until it encounters the con-

tact *e*' and forces the detaining member forward to align with the next rack or wheel space.

70

It will be observed that the hereinbefore-described invention results in a mechanism wherein the spacing of the carriage is effected at a uniform period and that immediately after the imprint of the type and practically simultaneously with the initial return of the vibratory members; wherein a shading or duplication of the said imprint is impossible from a hesitating or double blow or a tendency to not release the key promptly, as the spacing will not be accomplished until the key has been actually released; wherein the variance in the extent of the depression of the several key-levers is immaterial, as the carriage is released to space instantaneously with the initial return of the vibratory member actuating the spacing member; that is adapted to the needs of all speeds of operators, inasmuch as it does not space until the imprint is made irrespective of the style of touch of the operator, but spaces immediately after such imprint, thus enabling a low or moderate speed operator to use a machine having a high-speed escapement; that inasmuch as the spacing will be effected upon the initial return movement of the vibratory member the spacing member will be relieved to a great extent from the pressure exerted by the carriage-spring and the resulting friction and the spring tension required to return said vibratory member will be reduced to a minimum, with a resulting increase in the lightness of touch, and that may also be so adjusted as to meet the requirements of the individual operator.

105

It is not my intention to limit my invention to the precise construction herein shown and described, as it is obvious that it may be applied without material modification to all types of machines. If desired, the engaging member and its pivotal support may be made integral and vibratory instead of employing an interposed independent member, as herein shown and described; but the latter in practice has been found preferable, as it is applicable to both rack and wheel machines and capable of a more substantial structure and greater latitude in effecting the disengagement of the spacing member from the rack or ratchet mechanism. It is immaterial whether the rack or said members are vibratory. The spirit of my invention resides in a member of an escapement mechanism adapted to sustain the pressure of the mainspring during the direct throw of a vibratory member and to permit the spacing of the carriage either in full or in part immediately upon the initial return throw of said member, and it is my intention to claim such broadly.

Having described my invention, what I claim as new, and desire to have protected by Letters Patent, is—

1. In a type-writing machine, an escapement mechanism comprising a carriage-con-

trolling mechanism, a detaining member, a pivotal support, a vibratory member adapted to be actuated by the several key-levers whereby pressure from said carriage-controlling mechanism is transferred from said detaining member and applied to said support in opposite directions alternately, and means whereby movement of said support under such pressure is, during the direct movement 5 of said vibratory member, prevented to maintain the carriage stationary, said support being free to be swung upon its pivot instantly upon the initial return movement thereof by the resulting reversal of the direction of pressure thereon, to permit the spacing of the carriage.

2. In a type-writing machine, an escape-
ment mechanism comprising a carriage-con-
trolling mechanism, a detaining member, a
spacing member, a vibratory member adapted
to be actuated by the several key-levers
whereby pressure from said carriage-controlling
mechanism is transferred from said de-
taining member and applied to said spacing
member in opposite directions alternately,
and means whereby movement of said spacing
member under such pressure is, during the
direct movement of said vibratory member,
prevented to maintain the carriage stationary,
said spacing member being free to move in-
stantly upon the initial return movement
thereof under the resulting reversed direction
of pressure thereon, to permit the spacing of
the carriage.

3. In a type-writing machine, an escape-
ment mechanism comprising a carriage-con-
trolling mechanism, a detaining member,
spacing means consisting of a pivotal support
and an engaging member adapted to be con-
trolled by said support and to engage said car-
riage-controlling mechanism, means adapted
to be actuated by the several key-levers
whereby said detaining and said engaging
members are caused to successively engage
said carriage-controlling mechanism to trans-
fer the pressure therefrom from said detain-
ing member to said engaging member and ap-
ply it to said support in opposite directions
alternately and a stop whereby movement of
50 said support under such pressure is, during
the direct movement of said vibratory mem-
ber, prevented to maintain the carriage sta-
tionary, said support being free to be swung
upon its pivot instantly upon the initial re-
turn movement thereof by the resulting re-
versal of the direction of said pressure there-
on, to permit the spacing of the carriage.

4. In a type-writing machine, an escape-
ment mechanism comprising a carriage-con-
trolling mechanism, a detaining member,
spacing means consisting of a pivotal support
and an engaging member adapted to be con-
trolled by said support and to engage said car-
riage-controlling mechanism, means adapt-
ed to be actuated by the several key-levers
whereby said detaining and said engaging
members are caused to successively engage

said carriage-controlling mechanism to trans-
fer the pressure therefrom from said detain-
ing member to said engaging member and ap-
ply it to said support in opposite directions
alternately, a stop whereby movement of said
support under such pressure is, during the
direct movement of said vibratory member,
prevented to maintain the carriage station-
ary, said support being free to be swung upon
its pivot instantly upon the initial return
movement thereof by the resulting reversal
of the direction of said pressure thereon, to
permit the spacing of the carriage, and means
whereby said support is restored to its normal
position when said engaging member is dis-
engaged from said carriage-controlling mech-
anism.

5. In a type-writing machine, an escape-
ment mechanism comprising a carriage-con-
trolling mechanism, a detaining member,
spacing means consisting of a pivotal support
and an engaging member adapted to be con-
trolled by said support and to engage said car-
riage-controlling mechanism, means adapt-
ed to be actuated by the several key-levers
whereby said detaining and said engaging
members are caused to successively engage
said carriage-controlling mechanism to trans-
fer the pressure therefrom from said detain-
ing member to said engaging member and ap-
ply it to said support in opposite directions
alternately and an adjustable stop whereby
movement of said support under such pres-
sure is, during the direct movement of said
vibratory member, prevented to maintain the
carriage stationary, said support being free
to be swung upon its pivot instantly upon the
initial return movement thereof by the result-
ing reversal of the direction of said pressure
thereon, to permit the spacing of the carriage.

6. In a type-writing machine, an escape-
ment mechanism, comprising a carriage-con-
trolling mechanism, a detaining member,
spacing means consisting of an adjustable
plate, a pivotal support mounted thereon, a
stop whereby the movement of said support
in one direction is limited, an engaging mem-
ber adapted to be controlled by said support
and to engage said controlling mechanism and
means whereby said support is restored to its
normal position when said engaging member
is disengaged from said controlling mech-
anism, and means adapted to be actuated by
the several key-levers whereby said detain-
ing and engaging members are caused to suc-
cessively engage said controlling mechanism,
said engaging member while in contact with
said controlling mechanism during the direct
movement of said means being adapted un-
der the control of said support to maintain
the carriage stationary, and immediately upon
the initial return movement thereof to permit
the spacing of the carriage.

7. In a type-writing machine, an escape-
ment mechanism comprising a carriage-con-
trolling mechanism, a vibratory member, a
detaining member and an engaging member

carried thereby, said vibratory member being adapted to be actuated by the several key-levers to cause said detaining and said engaging member to successively engage said carriage-controlling mechanism, a pivotal support for said engaging member, a stop whereby movement of said support in one direction is limited, and means whereby said support is restored to its normal position when said engaging member is disengaged from said controlling mechanism, the pressure from said carriage-controlling mechanism being applied by said engaging member to said support in a direction to maintain said support in contact with said stop and thus hold the carriage stationary during the direct movement of said vibratory member, and immediately upon the initial return movement thereof, in the reverse direction to rotate said support away from said stop to permit the spacing of the carriage.

8. In a type-writing machine, an escape-
ment mechanism comprising a carriage-con-
trolling mechanism, a vibratory member, a
detaining and an engaging member carried
thereby, said engaging member being so fitted
in relation to said detaining member as to be
normally in close juxtaposition thereto and
to increase the distance therefrom during the
spacing interval, said vibratory member be-
ing adapted to be actuated by the several key-
levers to cause said detaining and said en-
gaging member to successively engage said
controlling mechanism, a pivotal support for
said engaging member, a stop whereby move-
ment of said support in one direction is lim-
ited, and means whereby said support is re-
stored to its normal position when said en-
gaging member is disengaged from said car-
riage-controlling mechanism, the pressure from
said carriage-controlling member being
applied by said engaging member to said sup-
port in a direction to maintain said support
in contact with said stop and thus hold the
carriage stationary during the direct move-
ment of said vibratory member, and imme-
diately upon the initial return movement
thereof, in the reverse direction to rotate said
support away from said stop to permit the
spacing of the carriage.

9. In a type-writing machine, an escape-
ment mechanism, comprising a carriage-con-
trolling mechanism, a detaining member, a
spacing means consisting of a pivotal sup-
port and an engaging member adapted to be
controlled by said support and to engage said
controlling mechanism, means adapted to be
actuated by the several key-levers whereby
said detaining and said engaging members
are caused to successively engage said con-
trolling mechanism, said engaging member
while in contact with said controlling mech-
anism during the direct movement of said
means being adapted under the control of
said support to maintain the carriage station-
ary, and immediately upon the initial return
movement thereof to permit the spacing of

said carriage, said engaging member being
mounted upon an inclined fulcrum-pin where-
by it is adapted to be fitted normally in close 70
juxtaposition to said detaining member and
to increase the space between them during
the spacing interval, whereby the disengage-
ment of said engaging member from said con-
trolling mechanism is facilitated.

10. In a type-writing machine, an escape-
ment mechanism comprising a carriage-con-
trolling mechanism, a detaining member, a
spacing member, means whereby said mem-
bers are caused to successively engage said 80
controlling mechanism, and an offset abut-
ment carried by one of said members and
adapted to engage the other toward the end
of the spacing interval whereby the length of
feed of the spacing member is regulated and 85
the detaining member is brought forward to
facilitate its reengagement with the carriage-
controlling mechanism.

11. In a type-writing machine, an escape-
ment mechanism comprising a carriage-con- 90
trolling mechanism, a detaining member, a
spacing member, means whereby said mem-
bers are caused to successively engage said
controlling mechanism, and an adjustable off-
set abutment carried by one of said members 95
and adapted to engage the other toward the
end of the spacing interval whereby the length
of feed of the spacing member is regulated
and the detaining member is brought forward
to facilitate its reengagement with the car- 100
riage-controlling mechanism.

12. In a type-writing machine, an escape-
ment mechanism comprising a carriage-con-
trolling mechanism, a detaining member, a
spacing member, means whereby said mem- 105
bers are caused to successively engage said
controlling mechanism and a stop having an
enlarged head and a screw-threaded shank,
carried by one of said members and adapted
to engage the other toward the end of the 110
spacing interval whereby the length of feed
of the spacing member is regulated and the
detaining member is brought forward to fa-
cilitate its reengagement with the carriage-
controlling mechanism.

13. In a type-writing machine, an escape-
ment mechanism comprising a carriage-con-
trolling mechanism, a detaining member, a
spacing member and means whereby said 120
members are caused to successively engage
said controlling mechanism comprising a main
vibratory member adapted to be actuated by
the several key-levers, an auxiliary vibratory
member adapted to actuate said detaining
and spacing members to cause them to suc- 125
cessively engage said controlling mechanism,
and a connection between said vibratory
members whereby motion is transmitted from
one to the other comprising a link, a swiveled
connection between said link and said auxil- 130
iary member, a similar connection between
said link and said main member comprising
an elongated loop encompassing a take-up
member carried by said member, whereby

movement of one member independently of that of the other is permitted and the extent of such movement is regulated.

14. In a type-writing machine, an escape-
ment mechanism comprising a carriage-con-
trolling mechanism, a detaining member, a
spacing member, and means whereby said
members are caused to successively engage
said controlling mechanism comprising a main
vibratory member adapted to be actuated by
the several key-levers, an auxiliary vibratory
member adapted to actuate said detaining
and spacing members to cause them to suc-
cessively engage said controlling mechanism,
a connection between said vibratory members
whereby motion is transmitted from one to
the other and means comprising a link at-
tached to said members by means of set-screws
whereby it may be adjusted toward or away
from the respective axes thereof to regulate
the comparative relative movement of said
members.

15. In a type-writing machine, an escape-
ment mechanism comprising a carriage-con-
trolling mechanism, a detaining member,
spacing means consisting of a pivotal support
and an engaging member adapted to be con-
trolled by said support and to engage said car-
riage-controlling mechanism, means adapted
to be actuated by the several key - levers
whereby said detaining and said engaging
members are caused to successively engage
said carriage-controlling mechanism to trans-
fer the pressure therefrom from said detain-
ing member to said engaging member and
apply it to said support in opposite directions
alternately, a stop whereby movement of said
support under such pressure is, during the di-
rect movement of said vibratory member, pre-
vented to maintain the carriage stationary,
said support being free to be swung upon its
pivot instantly upon the initial return move-
ment thereof by the resulting reversal of the
direction of said pressure thereon, to permit
the spacing of the carriage, means whereby
said support is restored to its normal position
when said engaging member is disengaged
from said carriage - controlling mechanism,
and means whereby positive force at the end
of the direct movement of said vibratory mem-
ber may be used to insure the initial unseat-
ing of said support.

16. In a type-writing machine, an escape-
ment mechanism comprising a carriage-con-
trolling mechanism, a detaining member,
spacing means consisting of a pivotal support
and an engaging member adapted to be con-
trolled by said support and to engage said car-
riage-controlling mechanism, means adapted
to be actuated by the several key-levers
whereby said detaining and said engaging
members are caused to successively engage

said carriage-controlling mechanism to trans-
fer the pressure therefrom from said detain-
ing member to said engaging member and
apply it to said support in opposite directions
alternately, a stop whereby movement of said
support under such pressure is, during the di-
rect movement of said vibratory member, pre-
vented to maintain the carriage stationary,
said support being free to be swung upon its
pivot instantly upon the initial return move-
ment thereof by the resulting reversal of the
direction of said pressure thereon, to permit
the spacing of the carriage, means whereby
said support is restored to its normal position
when said engaging member is disengaged
from said carriage - controlling mechanism,
and a buffer carried by said vibratory mem-
ber and adapted to contact with said support
whereby positive force at the end of the di-
rect movement of said vibratory member may
be used to insure the initial unseating of said
support.

17. In a type-writing machine, an escape-
ment mechanism comprising a carriage-con-
trolling mechanism, a detaining member,
spacing means consisting of a pivotal support
and an engaging member adapted to be con-
trolled by said support and to engage said car-
riage-controlling mechanism, means adapted
to be actuated by the several key - levers
whereby said detaining and said engaging
members are caused to successively engage
said carriage-controlling mechanism to trans-
fer the pressure therefrom from said detain-
ing member to said engaging member and
apply it to said support in opposite directions
alternately, a stop whereby movement of said
support under such pressure is, during the di-
rect movement of said vibratory member, pre-
vented to maintain the carriage stationary,
said support being free to be swung upon its
pivot instantly upon the initial return move-
ment thereof by the resulting reversal of the
direction of said pressure thereon, to permit
the spacing of the carriage, means whereby
said support is restored to its normal position
when said engaging member is disengaged
from said carriage - controlling mechanism,
and an adjustable buffer carried by said vi-
bratory member and adapted to contact with
said support whereby positive force at the
end of the direct movement of said vibratory
member may be used to insure the initial un-
seating of said support.

In witness whereof I have hereunto affixed
my signature, this 16th day of April, 1902, in
the presence of two witnesses.

LOUIS C. NEFF.

Witnesses:

WILLIAM E. DEANE,
FRANK P. WENTWORTH.
